YIELDING REED

Carl D. Brown, Hopedale, Mass., assignor to
Draper Corporation, Hopedale, Mass., a corpora-
tion of Maine

Application November 2, 1934, Serial No. 751,222

4 Claims. (Cl. 139—188)

The present invention pertains to looms and has more particular reference to the reed controlling instrumentalities of the yielding reed type of loom.

5 In looms of the type mentioned, the reed is mounted on the lay so as to be capable of relative rearward movement. The reed is normally held in its forwardmost position but is capable of yielding rearwardly at the time of beat-up, to thereby compensate for variations in the successive picks of filling. The spring means which control the reed at the time of beat-up are usually not sufficiently strong to prevent the reed from yielding during the time the shuttle is in flight.

10 In some types of looms, the shuttle cannot be properly controlled unless the reed and shuttle box are accurately aligned during the picking and boxing of the shuttle. Accordingly, a yielding of the reed at such times is most objectionable.

15

It has been proposed to support the yielding reed, while the shuttle is in flight, by supplementary spring devices. However, such devices are objectionable in that springs are inherently incapable of holding the reed with sufficient firmness unless the springs are objectionably heavy. Some such prior devices are further objectionable in that the springs must be stretched or compressed a considerable distance each pick of the loom with the result that the springs break and must be replaced frequently.

Accordingly, it is an object of the present invention to provide, in a yielding reed loom, positive locking means for the reed and positive means for moving the locking means to locking position as the lay moves rearwardly and from locking position as the lay moves forwardly.

Other objects will be hereinafter more specifically enumerated or will become apparent as the description proceeds.

The preferred embodiment of the present invention is illustrated on the accompanying drawings, of which:

Fig. 1 is a sectional view of the loom with the lay at front center;

Fig. 2 is a view similar to Fig. 1 but with the lay well back;

Fig. 3 is a rear elevation showing the right hand part of the reed mechanism, this view being to a larger scale than Figs. 1 and 2; and

Fig. 4 is a sectional view, taken approximately on line 4—4 of Fig. 3.

The loom to which my invention has been applied is but fragmentarily illustrated on the drawings, there being shown only one side of

the reed mechanism (it being understood that the mechanism shown is duplicated at the other side of the loom) and certain contiguous parts. The loom frame includes loom sides, of which the right hand loom side 1 is shown, and which are connected by cross members including a breast beam 2.

The lay 3 is mounted on lay swords, as 4, for reciprocation toward and from the front of the loom in the usual manner. A conventional reed 10 5 is mounted so as to normally move with the lay but to yield rearwardly at the time of beat-up, as is usual in yielding reed looms. The reed is conveniently rendered capable of rearward movement by mounting it in a reed structure 15 which is pivoted on studs, as 6, in brackets, as 7, carried by the lay swords.

The reed structure shown includes a hand rail 8 bolted at each end to a side lever 9. The lever 9 is fulcrumed on the stud 6 and extends downwardly therefrom. A lower reed holding bar 10 and warp supporting bar 11 are fastened together as by bolts 12 and each end of this assembly is fixed to and supported by the lower end of a lever 9, as by means of a bolt 13. The 25 reed is supported between the hand rail and the bar 10 and is thus mounted to move rearwardly by pivoting with the reed structure about the axis of stud 6.

The reed structure and reed may be yielding- 30 ly held forwardly by any suitable means. There is shown, for this purpose, a series of bolts 14 extending through the lay and upturned at 15 to engage back of the reed structure, the bolts being urged forwardly by springs 16 positioned between the lay and the nuts threaded onto the bolts. The limit of forward movement of the reed may be adjustably determined by the heads of stop bolts, as 17, Fig. 4.

The mechanism as thus far described would 40 not only permit the reed to yield at the time of beat-up but would also permit such yielding when the lay is back and the shuttle in flight. It is with means for preventing this latter yielding that the present invention is concerned.

It will be noted that the bracket 7 is fixed with respect to the lay and that a part 18 thereof projects downwardly and rearwardly to a point well back of the lay. A locking member 19 is movably mounted on the part 18, as by being pivoted on a 50 stud 20 therein. This stud is preferably of the eccentric type, for adjusting the position of the locking member. The locking member occupies the position as shown by Figs. 1 and 3 only during the actual beat-up, (which is while the lay is 55

at and near front center). At such time, the locking member is entirely free of the reed structure and has no effect on the yielding of the reed. However, the locking member can be moved so that it extends between the part 18 and the reed frame and positively locks the reed against yielding, as shown by Fig. 2. Preferably, the locking member is provided with a cam surface 21, eccentric of stud 20, which surface engages a projection 22 on lever 9 of the reed structure.

10 The member 19 is moved to and from locking position in synchronism with the movement of the lay, being moved to locking position as the lay moves rearwardly and from such position as the lay approaches the limit of its forward movement. The means disclosed for moving the locking member is positive in action and may consist simply of a link 23 pivoted at its lower end on a fixed pivot 24 and at its upper end to the locking member 19. The pivot 24 may be carried by a bracket 25 fixed to the loom side. The pivot is positioned to the rear of the rock shaft 26 and will therefore cause the link to swing the locking member upwardly and downwardly as the lay reciprocates. The link 23 shown on the drawings is threaded so as to be adjustable for varying the time of locking and unlocking the reed.

15 Having fully disclosed the preferred embodiment of my invention, I claim:

20 1. In a loom, a reciprocating lay, a spring-controlled reed structure and reed mounted on the lay to yield rearwardly at the time of beat-up, a stand fixed with respect to the lay, a locking member pivoted on said stand and engaging said 25 reed structure for positively locking the same against rearward movement as the lay moves rearwardly, the pivot for said locking member being comprised of an eccentric stud for adjusting said member toward and from said reed structure, and means for pivoting said member about said stud out of locking position as the lay approaches the limit of its forward movement.

2. In a loom, a reciprocating lay, a reed struc-

ture and reed pivoted with respect to the lay above the cloth, spring means yieldingly resisting rearward pivoting of said structure at the time of beat-up, a stand projecting rearwardly of the lay, a locking member mounted on said stand and engaging behind said reed structure to positively hold the same against rearward yielding as the lay moves rearwardly, and means for withdrawing said locking member from locking position as the lay approaches the limit of its forward movement.

3. In a loom, a reciprocating lay, a spring-controlled reed structure and reed mounted on the lay to yield rearwardly at the time of beat-up, a stand fixed with respect to the lay, a cam member pivoted to said stand at a point horizontally rearwardly of said reed structure, said member being movable on said pivot to and from position where it engages behind said reed structure and locks the same against rearward yielding, and a link pivoted at one end on a fixed pivot and at its other end to said cam member, said link moving said cam member to said locking position as the lay moves rearwardly and away from said position as the lay approaches the limit of its forward movement.

4. In a loom, a reciprocating lay, a reed structure and reed pivoted with respect to the lay above the cloth, spring means yieldingly resisting rearward pivoting of said structure at the end of beat-up, a stand projecting rearwardly from the lay, a locking cam pivoted on said stand at a point horizontally rearwardly of said reed structure for movement to and from position where it engages said reed structure and positively locks the same against rearward movement, and a link pivoted at one end on a fixed pivot and at its other end to said cam for swinging the latter to locking position as the lay moves rearwardly and from locking position as the lay approaches the limit of its forward movement.

CARL D. BROWN.
